UNITED STATES PATENT OFFICE

2,595,006

APPARATUS FOR HANDLING HOT METAL RODS

John W. Sheperdson, Worcester, Mass., assignor
to Morgan Construction Company, Worcester,
Mass., a corporation of Massachusetts

Application March 23, 1950, Serial No. 151,395

2 Claims. (Cl. 34—105)

1

This invention relates to apparatus for handling hot metal rods, and more particularly to apparatus including a plurality of reels adapted to form such rods into annular bundles as they are delivered by a rolling mill, and means for conveying the bundles away from the reels.

In the usual rod mill it is customary to provide a plurality of reels in a row at one side of a bundle conveyor and closely adjacent thereto, so that completed bundles may be discharged directly from the reels to the conveyor. The conveyor usually comprises a generally horizontal plate structure having two parallel slots therein, with a longitudinally traveling chain located beneath each slot to carry a series of dogs which project upwardly through the slot. The dogs on the respective chains are aligned laterally so that each pair of dogs may serve to push an annular rod bundle along the plate structure. In order that the reels may be employed efficiently and that a minimum number of reels may be required to handle the product of a particular rolling mill, it is important to discharge the bundles from the reels as soon as they are completed, so that each reel may be quickly prepared to receive another rod. With the usual arrangement of apparatus, however, it is often not possible to discharge a completed bundle immediately, since the conveyor space opposite the loaded reel may be already occupied by a bundle from one of the other reels, or one pair of the conveyor dogs may be in a position to interfere with the discharge of the bundle. Consequently it has frequently been necessary to operate a rod mill at less than its full capacity, because of delay in the emptying of the reels.

It is accordingly one object of the invention to provide a novel arrangement of rod reels and an associated rod bundle conveyor such that completed bundles may be discharged promptly from the reels.

It is a further object of the invention to provide an arrangement of apparatus, including a group of rod reels and an associated rod bundle conveyor, adapted not only to facilitate prompt discharge of completed bundles from the reels but also to effect rapid cooling of the bundles and thereby avoid the formation of excessive scale thereon.

With these and other objects in view, as will be apparent to those skilled in the art, the invention resides in the combination of parts set forth in the specification and covered by the claims appended hereto.

In accordance with the invention there is provided a plurality of reels each arranged to re-

2

ceive a longitudinally traveling hot metal rod and to form the same into an annular bundle. These reels may be of any suitable type, for example pouring reels or laying reels. There is further provided a conveyor which is arranged to move rod bundles in a generally horizontal direction. This conveyor is preferably of the type which includes a series of longitudinally spaced pairs of laterally adjacent abutments adapted to engage the rod bundles from the rear and to push them along with their axes upright. Adjacent each reel there is provided a delay station to which a bundle may be transferred from the reel by a reel discharge mechanism and from which a bundle may be moved onto the conveyor by a transfer mechanism operable independently of the reel discharge mechanism. With this construction a completed bundle may be discharged immediately from a reel to the corresponding delay station even though the conveyor may not be in condition at the moment to receive such bundle, and the reel may therefore receive another rod and begin forming it into a new bundle at once. The discharged bundle may remain at the delay station until an empty space on the conveyor arrives opposite the delay station, whereupon the bundle may be transferred to the said empty space. Thus each reel may be operated at its full capacity. Each delay station may be provided with means to blow air through the convolutions of a bundle located thereon, and in this manner the bundles may be cooled rapidly while they are awaiting transfer to the conveyor. This will prevent excessive scale formation on the bundles.

Referring to the drawings illustrating one embodiment of the invention and in which like reference numerals indicate like parts,

Fig. 1 is a plan view of a rod handling apparatus shown partially in section along the line 1—1 of Fig. 3;

Fig. 2 is an enlarged plan view of a portion of the apparatus shown in Fig. 1, the section being taken at a somewhat lower plane as indicated by the line 2—2 of Fig. 3, certain parts being broken away for clearness of illustration;

Fig. 3 is a vertical section taken on the line 3—3 of Fig. 2; and

Fig. 4 is a fragmentary view taken in section on the line 4—4 of Fig. 3.

The embodiment illustrated comprises a rod bundle conveyor 10 of a well-known type including an elongated horizontal plate 11 having two longitudinally extending parallel slots 12 therein. An endless chain 14 travels along each slot 12,

and each chain carries a series of dogs 15 which project above the plate 11. The dogs on the respective chains are arranged in lateral alignment, and each pair of laterally adjacent dogs may serve to push a rod bundle B along the conveyor with the axis of the bundle upright.

At one side of the conveyor 10 there is located a series of reels 17 arranged in a row extending parallel with the conveyor but spaced a short distance therefrom. These reels 17 may be of any type adapted to receive a rapidly traveling hot metal rod and to form it into an annular bundle. The particular reels illustrated are of the well-known pouring type, each reel comprising a horizontal circular coil plate 18 (Fig. 2) which is rotated about a vertical axis by means of an electric motor 19, the motor being connected to the coil plate by means of suitable gearing enclosed in a gear box 21 (Fig. 3). Each plate 18 is provided with an inner row of openings 22 and an outer row of openings 23, both rows being in the form of circles coaxial with the plate. Pins 25 extend upwardly through the openings 22, and pins 26 extend upwardly through the openings 23. It will be understood that a longitudinally traveling hot metal rod will be delivered through a guide pipe (not shown) in a downwardly inclined and generally tangential direction to the annular space between the two rows of pins 25 and 26, so that an annular coil or bundle will be formed within the said annular space. Upon completion of the bundle, the electric motor 19 will be stopped, and the coil plate 18 will be raised to lift the bundle above the level of the tops of the pins 25 and 26, so that the bundle may be discharged laterally from the plate. The raising and lowering of the plate 18 is accomplished by means of a hydraulic motor 28 (Fig. 3) which is connected by a link 29 to a lever 30. One end of this lever is fulcrumed on a pin 32, and the other end is connected by a link 33 to a vertical rod 34 which extends upwardly through the gear box 21 in a position coaxial with the coil plate 18. This rod serves to raise and lower the plate in known manner.

Between each reel 17 and the conveyor 10 there is provided a horizontal plate or platform 36 forming a delay station on which a bundle discharged from the reel may rest for a while before it is transferred to the conveyor. The upper surface of this plate 36 is preferably substantially level with the top of the conveyor plate 11 and with the top of the coil plate 18 when the latter is in its raised or discharge position. Each reel 17 is provided with a separate mechanism for discharging bundles to the corresponding delay station. For this purpose a generally horizontal arm 38 is secured at one end to the upper end of a vertical shaft 39 which is rotatably supported in a bearing 40 on one side of the reel housing. This arm 38 is arranged to swing horizontally over the top of the coil plate 18, when the latter is raised, and thereby sweep a completed rod bundle from the coil plate to the delay station platform 36. The arm carries a pair of shoes 42 which engage the bundle during this operation. To actuate the arm 38 there is provided a hydraulic motor 43 which drives a reciprocable horizontal rack 44 meshing with a gear segment 45 secured to the lower end of the shaft 39. Similarly each delay station 36 is provided with a separate mechanism for transferring bundles therefrom to the conveyor 10. Each such mechanism comprises a generally hor-

izontal arm 47 fastened at one end to the upper end of a vertical shaft 48 which is rotatably supported in a bearing 49 on one side of the platform 36. This arm carries a pair of shoes 51 arranged to engage a bundle and to sweep it from the platform 36 to the conveyor 10. The arm is actuated by a hydraulic motor 52 which drives a reciprocable horizontal rack 53, this rack meshing with a gear segment 54 fastened to the lower end of the shaft 48. It will be understood that the admission of pressure fluid to each of the motors 43 and 52, and the discharge of fluid therefrom, will be controlled by valves (not shown) of a suitable and well-known type.

In some cases it is desirable to cool the bundles of rod quickly in order to minimize the formation of scale thereon. This may be accomplished by blowing cool air through the convolutions of the bundles while they are positioned at the delay stations. For this purpose each delay station platform 36 is provided with a group of closely spaced openings 60 extending through the platform in position to be surrounded by a bundle B when the latter is discharged from the corresponding reel 17, as best shown in Fig. 2. A fan 61 (Figs. 3 and 4) is located beneath each platform 36 and arranged to blow air upwardly through a duct 62 to the openings 60. The wheel or impeller of each fan is rotated by a shaft 63 driven by an electric motor 65 (Fig. 3). In order that the air delivered upwardly through the openings 60 will be compelled to flow outwardly through the convolutions of the rod bundle, a horizontal circular plate 67 somewhat exceeding the bundle in outside diameter is placed on the top of the bundle. One of these plates is provided at each delay station. Each plate 67 is suspended by cables 68 or the like from the piston rod of a vertical hydraulic motor 70, so that the plates may be raised and lowered as desired. The motors 70 are mounted on a suitable supporting structure 71 above the delay stations.

The operation of the invention will now be apparent from the above disclosure. Hot metal rods produced by a rolling mill will be delivered through the usual guide pipes (not shown) to the reels 17, which will form the rods into annular bundles B in the usual manner. As each reel completes a bundle, the corresponding driving motor 19 will be stopped, the hydraulic motor 28 will be energized to raise the coil plate 18 and the bundle above the tops of the pins 25 and 26 in the usual way, and the hydraulic motor 43 will be energized to swing the arm 38 to the position indicated by broken lines in Fig. 2, thereby sweeping the bundle from the coil plate 18 to the delay station platform 36 in a position surrounding the group of air openings 60. The coil plate 18 will thereupon be lowered, the motor 19 started, and the arm 38 returned to its original position, so that the reel 17 will be in condition to receive another rod immediately. In the meantime the plate 67 will be lowered to engage the top of the bundle on the platform 36, and the fan 61 will blow air upwardly through the duct 62 and the openings 60 into the interior of the bundle and thence radially outward through the convolutions of the bundle to cool the same. The bundle can be retained on the platform 36 until the continuous movement of the conveyor chains 14 causes an "empty" pair of dogs 15 to approach, whereupon the plate 67 will be lifted from the bundle and the hydraulic motor 52 will be ener-

gized to swing the arm 47 to the position indicated by broken lines in Fig. 2, thus sweeping the bundle from the delay station to the conveyor plate 11 in position to be engaged by the approaching dogs. The arm 47 will then be returned to its original position.

The invention makes it possible to discharge each bundle from a reel as soon as the bundle is completed and regardless of whether or not the conveyor 10 is able to take immediate delivery of the bundle. Thus each reel may be operated more efficiently, and more bundles per hour can be formed therein. Furthermore, each bundle may be effectively cooled while it rests at the delay station 36, so that very little scale will form on the bundles.

Having thus described my invention, what I claim as new and desire to secure by Letters Patent is:

1. Apparatus for handling hot metal rods comprising a plurality of reels each arranged to receive a rod and to form the same into an annular bundle, a conveyor arranged to move rod bundles in a generally horizontal direction, the reels being spaced slightly from the conveyor, a substantially horizontal platform between each reel and the conveyor and forming a delay station, the platform having a group of openings therethrough, means to transfer bundles from each reel to the corresponding platform in a position directly above the group of openings, means to blow air upwardly through the openings, a plate supported above each platform and arranged to be lowered on to a bundle to deflect the air laterally through the convolutions of the bundle, and means to transfer bundles from each delay station to the conveyor and operable independently of the first mentioned transfer means

2. Apparatus for handling hot metal rods com-

prising a plurality of aligned reels each arranged to receive a rod and to form the same into an annular bundle, a generally horizontal conveyor substantially parallel to said aligned reels having a series of longitudinally spaced traveling abutments arranged to engage rod bundles and to move the bundles along the conveyor with their axes upright, the reels being spaced slightly from the conveyor, a substantially horizontal platform whose center is located between each reel and the conveyor on a perpendicular line from the center of the reel to the center-line of the conveyor and forming a delay station, means to discharge bundles from each reel to the corresponding platform, a generally horizontal arm supported about an upright axis near each platform in position to sweep bundles from the platform and on to the conveyor, and means to actuate each arm independently of the said discharge means.

JOHN W. SHEPERDSON.
